UNITED STATES PATENT OFFICE.

GEORGE ALBERT LEEKS, OF HAMILTON, ONTARIO, CANADA, ASSIGNOR TO STOPGLARE, LIMITED, OF HAMILTON, ONTARIO, CANADA, A CORPORATION OF CANADA.

DESIGN FOR A HEADLIGHT-LENS.

51,648.

Specification for Design.

Patented Jan. 1, 1918.

Application filed November 17, 1917. Serial No. 202,656. Term of patent 14 years.

To all whom it may concern:

Be it known that I, GEORGE ALBERT LEEKS, a subject of the King of England, residing at Hamilton, in the county of Wentworth, Province of Ontario, and Dominion of Canada, have invented a new, original, and ornamental Design for Headlight-Lenses, of which the following is a specification, reference being had to the accompanying drawings, forming part thereof.

Figure 1 is an elevation of a headlight lens showing my new design. Fig. 2 is a section of the same taken in line 2—2, Fig. 1.

I claim:

The ornamental design for a headlight lens, as shown.

GEORGE ALBERT LEEKS.
